(57) **CLAIM**

The ornamental design for an electric motorcycle, as shown and described.

DESCRIPTION

1. Electric motorcycle
- 1.1 : Front
- 1.2 : Back
- 1.3 : Left
- 1.4 : Right
- 1.5 : Top
- 1.6 : Bottom
- 1.7 : Perspective
- 1.8 : Perspective

Fig. 1.1 is a front view of an electric motorcycle embodying our new design; fig. 1.2 is a back view thereof; fig. 1.3 is a left view thereof; fig. 1.4 is a right view thereof; fig. 1.5 is a top view thereof; fig. 1.6 is a bottom view thereof; fig. 1.7 is perspective view 1 thereof; fig. 1.8 is perspective view 2 thereof.

1 Claim, 8 Drawing Sheets
